CLEANING TOOL FOR TUBES

Charles E. Cournoyer, Port Washington, and
Robert R. Charron, New York, N. Y.

Application January 16, 1946, Serial No. 641,552

5 Claims. (Cl. 15—4)

(Granted under the act of March 3, 1883, as
amended April 30, 1928; 370 O. G. 757)

1

The present invention concerns a tool for swabbing a bore surface, and particularly concerns a tool for swabbing the bore surface of a torpedo tube.

In cleaning the internal bore of a torpedo tube after firing operations and during subsequent overhauling, or in cleaning preservative solution from the bore of a torpedo tube which has been previously cleaned and preserved, it is necessary to apply cleaning solution uniformly over the entire surface of the bore to loosen the dirt or preservative solution and then to remove the material to leave a clean surface. Similarly in lubricating or preserving a torpedo tube it is necessary to apply lubricating or preserving fluid uniformly over the entire surface of the bore, and then to remove the excess fluid to leave a uniform thin coating.

It is customary both in applying and removing fluid relative to a torpedo-tube bore to use a swabbing tool consisting of a long handle having on one end a swabbing element such as, for example, a tuft of rags. The swabbing element end of the tool is inserted into the bore and by means of the handle an operator manipulates the swab portion of the tool over the entire surface of the bore. Such manual use of a conventional swabbing tool has proven unsatisfactory in several respects.

It has been found difficult and often impossible properly to manipulate the tool so that all areas of the bore surface are swabbed uniformly. This is especially true in relatively long bores where inordinate length of the tool handle renders manipulation difficult and where it is difficult to see the remote areas being treated. These difficulties have resulted in poor cleaning operations. Furthermore, since the quality of the cleaning operation depends upon the dexterity of the individual operator, it is apparent that the results produced by different operators vary and the results achieved even by the same operator on different cleaning jobs will vary. A further objection has arisen because of the excessive amount of time and labor involved in performing the swabbing operation as well as the increased time and labor required from inspectors in detecting and rejecting unsatisfactory cleaning jobs resulting from unsatisfactory cleaning operations.

The swabbing tool that forms a preferred embodiment of the invention overcomes these defects by achieving the following objects.

An object of the invention is to provide a swabbing tool that may be manipulated relative to a

2

bore so that all areas of the bore surface are uniformly swabbed.

Another object is to provide a swabbing tool that is so constructed that if malfunctioning of the tool occurs during operation, the tool will fracture or break before damage such as scarring or marring of the bore surface occurs thus insuring safety of operation and precluding possibility of damage to the bore surface by the malfunctioning tool.

Another object is to provide a swabbing tool that is designed so that the swabbing element is arranged for circumferential and longitudinal swabbing motion on the bore surface, and these motions may be combined to affect any type of swabbing motion desired.

Another object is to provide a swabbing tool for use in relatively long cylindrical bores which comprises a relatively long handle having a disc shaped swabbing element at one end arranged for rotary and reciprocating motion and a radial supporting element on the handle for retaining the latter in the line of the longitudinal axis of the bore during operation and to prevent whipping and vibration in the handle during operation.

Further objects and advantages of this invention, as well as its construction, arrangement and operation, will be apparent from the following description and claims in connection with the accompanying drawing, in which,

Fig. 1 is a longitudinal sectional view of a preferred embodiment of the invention illustrated as being used for cleaning a torpedo tube.

Fig. 2 is a fragmentary cross-sectional view taken along line 2—2 of Fig. 1.

Fig. 3 is an elevational view of the swab holding disc when seen as viewed from the right of Fig. 1, and

Fig. 4 is a fragmentary sectional view similar to Fig. 2 showing a modified form of the invention.

In the drawing there is shown a torpedo tube liner 11 which is in the form of a cylindrical shell 45 and provided with a cylindrical bore 12. Formed longitudinally in the top of liner 11 is a T-shaped groove 13 having a stem portion 14 and a cross-head portion 15.

Swabbing tool 16 comprises a shaft 17 with threads 18 at one end, and at the other end provided with a shank portion 19 which may be coupled with a suitable source of power (not shown) or which may be used as a handle for manual operation by an operator to effect rotation and reciprocation of the tool during a clean-

ing operation. Shaft 17 may be formed of metal or any other suitable material.

Mounted transversely on the threaded end of shaft 17 is a swab holder disc 20 which may be formed of plywood or any other suitable material. Disc 20 is fitted over threads 18 and is reinforced centrally on opposite faces thereof by brace plates 21 and 22 which may be formed of metal. Disc 20 and brace plates 21 and 22 are locked together rigidly upon threads 18 by means of lock nuts 23 and 24 so that disc 20 will rotate with shaft 17. Mounted peripherally on one face of disc 20 are multiple swab clamps 25 each of which consists of a U-shaped portion 26 and legs 27 which are secured to disc 20 by means of screws 28.

Removably mounted on disc 20 by means of clamps 25 are multiple swab elements 29 which may be formed of rags or other suitable material. Swabbing elements 29 are tightly held in place by clamps 25 and are arranged to protrude beyond the periphery of disc 20 into contact with torpedo tube bore surface 12.

Mounted on shaft 17 adjacent disc 20 is a hanger 30 consisting of a collar 31 which fits loosely over shaft 17, a radially extending web portion 32 integral with collar 31 and a T-head 33 formed integrally at the outer end of web 32. The opposite ends of head 33 are beveled to provide parallel faces 34 and 35 and to provide scraping edges 36 and 37. Scraping edge 36 is formed along the radially outward surface 38 of T-head 33 while scraping surface 37 is formed along the radially inward surface 39 of T-head 33. T-head 33 is adapted to slide within groove 13 formed in torpedo tube liner 11 with T-head 33 disposed in portion 15 of the groove and web 32 extending through portion 14 of the groove.

Slidably mounted on shaft 17 is a stop collar 40 which may be locked rigidly to shaft 17 in any desired position by set screw 41. Collar 40 serves to limit the movement of hanger 30 on shaft 17 in a direction away from disc 20.

Mounted on shaft 17 between collar 40 and shank 19 is a second hanger 42 comprising collar 43, web 44 and T-head 45 having scraping edges 46 and 47. Preferably, hanger 42 is mounted on shaft 17 so that scraping edges 46 and 47 are in reversed position with respect to scraping edges 36 and 37 of hanger 30. That is, scraping edge 36 of hanger 30 which is in the top of groove 13 faces toward disc 20 whereas scraping edge 46 of hanger 42 which is in the top of groove 13 faces away from disc 20. The relative arrangement of hangers 34 and 42 on shaft 17 is optional.

In Fig. 4 is shown a modified embodiment of the invention. Parts which are similar to those described in connection with Figs. 1-3 have been given identical reference characters and those parts which distinguish from Figs. 1-3 and will now be described.

A cylindrical shell 48 is shown as having a bore surface 49 which is not provided with a groove similar to groove 13 of Fig. 2. Hanger 50 comprises a collar 51 fitting loosely about shaft 17 and provided with oppositely extending webs 52 and 53, terminating in T-heads 54 and 55 which are adapted to engage bore surface 49 and which may be similar in design to T-head 33 of hanger 30 shown in Fig. 1 and thus serve as scrapers for bore 49.

Operation of the swabbing tool will now be described. The preferred form of swabbing tool 16 is prepared for use by tightening collar 40 in

the desired position on shaft 17 so that hanger 30 may be allowed optimum range of movement on shaft 17 away from disc 20. The position of collar 40 will depend upon the length of shaft 17 and the degree of insertion of tool 16 into bore 12. Swab elements 29 are then inserted into clamps 25. T-heads 33 and 45 of hangers 30 and 42 respectively are inserted into groove 13 of torpedo tube liner 11. Swabbing tool 16 is then coupled by shank 19 to a power source (not shown) such as a pneumatic power unit or shank 19 may be gripped as a handle for manual control by an operator.

Tool 16 is then operated either manually or by a power source to cause rotation and reciprocation of shaft 17 and this in turn causes rotation and reciprocation of swabbing elements 29 to cause swabbing of the desired areas of bore surface 12. By combining the rotary and reciprocating motions of tool 16 any desired motion of swabbing elements 29 may be effected. If it is desired to apply a liquid solution to bore surface 12, such solution may be applied to swab elements 29 or spilled on the bore surface 12 so that manipulation of tool 16 will spread such a cleaning solution as a film upon bore surface 12.

During such operation, reciprocation of shaft 17 will cause hangers 30 and 42 to slide relative to torpedo tube liner 11 so that scraping edges 36 and 46 respectively, will scrape the top of groove 13 while scraping edges 37 and 47 scrape the bottom of groove 13. With hangers 30 and 42 disposed as shown in Fig. 1 with the scraping edges in reversed relation it will be seen that both the top and bottom of groove 13 will be scraped regardless of the direction of reciprocation of hangers 30 and 42. Thus, for example, if movement is toward disc 20 the upper surface of groove 13 will be scraped by scraping edge 36, whereas if movement is away from disc 20, upper surface of groove 13 will be scraped by scraping edge 46. Such scraping action tends to clean the surface of groove 13 and in addition serves to detect any burrs or other defects in the walls of groove 13 since the scraping edges of hangers 30 and 42 catch upon such defects which may then be readily located by an operator. In addition to the scraping and detecting functions of T-heads 33 and 45 hangers 30 and 42 respectively serve to support and guide shaft 17 along the axis of bore 12 and in addition serve to prevent whipping and vibration of shaft 17 during operation.

Due to the loose fit of collars 31 and 43 upon shaft 17 any minor local bunching or jamming of swab elements 29 or any other minor malfunctioning of tool 16 may be automatically corrected by rocking of shaft 17 with respect to collars 31 and 43 and consequently wobbling of disc 20.

Major malfunctioning of tool 16, however, of such magnitude that it is not automatically self-correcting will cause breaking of disc 20 under the force of manipulation of tool 16 and thus prevent damage of bore surface 12 by scarring from the malfunctioning tool.

Operation of the modified form of tool shown in Fig. 4 is similar to that just described except that T-heads 54 and 55 of hanger 50 are disposed in sliding contact with bore surface 49 instead of being disposed within a groove such as groove 13 shown in Figure 2. T-heads 54 and 55 in operation serve to scrape bore surface 49 to clean same and to detect any burrs thereon while collar 51 of hanger 50 serves to support guide shaft 17 along the longitudinal axis 49 and prevent whip-

ping and vibration of shaft 11. While use of the swabbing tool of this invention has been described in connection with cylindrical bores, it will be appreciated that bores having cross-sections of various shapes may be cleaned with equal efficiency.

It is to be understood that various modifications and changes may be made in this invention without departing from the spirit and scope thereof as set forth in the appended claims.

The invention described herein may be manufactured and used by or for the Government of the United States of America for governmental purposes without the payment of any royalties thereon or therefor.

What is claimed is:

1. A tool for swabbing a longitudinal bore surface formed internally of a body comprising a relatively long shaft having at one end a shank adapted for connection to a source of power for actuating said shaft and at its other end having rigidly attached thereto a transverse member having a periphery, multiple clamps mounted peripherally on said member, multiple swabbing elements detachably secured to said member by said clamps, said swabbing elements being mounted to protrude beyond the periphery of said member, a hanger disposed adjacent said member for supporting said shaft centrally relative to the bore comprising a collar fitting loosely about said shaft, a radially extending web formed integrally with said collar and a longitudinally extending T-head formed integrally with the end of said web remote from said collar and adapted for contact with the body, said T-head having scraping edges formed on opposite ends thereof, and an adjustable collar on said shaft disposed on the side of the hanger opposite from the transverse member and adapted to be locked to said shaft to limit the distance said hanger collar may slide relative to said shaft in a direction away from said member.

2. A tool for swabbing the bore of a torpedo tube comprising a shaft exceeding in length the torpedo tube bore-length and adapted to be positioned along the longitudinal axis of the bore, said shaft having at one end a shank adapted for connection to a source of power for rotating and reciprocating said shaft and at its other end having rigidly attached thereto a transverse disc of diameter less than the bore of the torpedo tube and adapted to be rotated and reciprocated with said shaft within the torpedo tube, multiple clamps mounted peripherally on said disc, multiple swabbing elements detachably secured to said disc by said clamps, said swabbing elements being mounted to protrude beyond the periphery of said disc and being adapted to contact the torpedo tube bore surface, a hanger disposed adjacent said disc for supporting said shaft centrally relative to the torpedo tube comprising a collar fitting loosely about said shaft, a radially extending web formed integrally with said collar and a longitudinally extending T-head formed integrally with the end of said web remote from said collar, said T-head being adapted for sliding engagement in a longitudinal T-shaped slot formed in the torpedo tube, said T-head having front and rear ends which are bevelled to provide parallel faces and form front and rear scraping edges with the scraping edge on one of said faces formed on the radially outward surface of said T-head and the scraping edge on the other of said faces formed on the radially inward surface of the T-head, an ad-

justable collar on said shaft disposed on the side of the hanger opposite from the transverse disc and adapted to be locked to said shaft to limit the distance said hanger collar may slide relative to said shaft in a direction away from said disc.

3. A tool for swabbing a longitudinal bore surface formed internally of a body comprising a relatively long shaft having at one end a shank adapted for connection to a source of power for actuating said shaft and at its other end having rigidly attached thereto a transverse member having a periphery, multiple clamps mounted peripherally on said member, multiple swabbing elements detachably secured to said member by said clamps, said swabbing elements being mounted to protrude beyond the periphery of said member, a hanger disposed adjacent said member for supporting said shaft centrally relative to the bore comprising a collar fitting loosely about said shaft, a radially extending web formed integrally with said collar and a longitudinally extending T-head formed integrally with the end of said web remote from said collar and adapted for contact with the body, said T-head having scraping edges formed on opposite ends thereof, an adjustable collar on said shaft disposed on the side of the hanger opposite from the transverse member and adapted to be locked to said shaft to limit the distance said hanger collar may slide relative to said shaft in a direction away from said member, and a second hanger similar to said first hanger and disposed on said shaft on the side of said adjustable collar away from said first hanger.

4. A tool comprising a shaft, a transverse member attached to one end of said shaft, a clamp mounted on said member and adapted to hold detachably a swab and so positioned that such swab is operative at a predetermined distance from the axis of said shaft, and a hanger for supporting said shaft and freely movable longitudinally of said shaft and comprising an element positioned radially a predetermined distance from said axis greater than the first-mentioned distance, said element being provided with scraping edges at the extremity remote from said shaft.

5. A tool comprising a shaft, a transverse member attached to one end of said shaft, a clamp mounted on said member and adapted to hold detachably a swab and so positioned that such swab is operative at a predetermined distance from the axis of said shaft, and a hanger for supporting said shaft and freely movable longitudinally of said shaft and comprising an element positioned radially a predetermined distance from said axis, said element being provided with scraping edges at the extremity remote from said shaft.
